and will light area of the recording device and will be broken when the beam 12 is rotated. The coil spring 27 may be made of any suitable material and it is desired to have the coil spring 27 made of a metal such as steel or chrome and the hub 21 and shaft 22 made of a metal such as aluminum or brass. The coil spring 27 is mounted with its span between the hub 21 and the shaft 22.

UNITED STATES PATENT OFFICE

Patent or Registration Number 1,983,872

RECORDING DEVICE FOR LOOMS

Oscar V. Payne, Worcester, Mass., assignor to Crompton & Knowles Loom Works, Worcester, Mass., a corporation of Massachusetts

Application October 30, 1930, Serial No. 492,257

6 Claims. (Cl. 234—1)

This invention relates to a device adapted to record certain data relative to the operation of a loom.

It is the general object of the invention to provide a device which will give a graphic indication of the regularity or irregularity of a selected loom operation, such as the movement of the warp beam in letting off or feeding warp threads to the loom harnesses.

A further object of the invention is to provide a device in which back lash is substantially eliminated, and which is directly responsive to reproduce the movements of a warp beam or other loom part on an enlarged scale and to provide a permanent record thereof.

My invention further relates to arrangements and combinations of parts which will be hereinafter described and more particularly pointed out in the appended claims.

A preferred form of the invention is shown in the drawings, in which

Figure 1 is a side elevation of parts of a loom showing my recording device applied thereto;

Fig. 2 is a side elevation of the recording device on an enlarged scale;

Fig. 3 is a sectional front elevation, taken along the line 3—3 in Fig. 2;

Fig. 4 is a plan view of the device;

Fig. 5 is a detail sectional side elevation, taken along the line 5—5 in Fig. 4; and

Fig. 6 is a detail sectional view, taken along the line 6—6 in Fig. 4.

Referring to Fig. 1, I have shown my recording device as mounted upon a bracket 10 secured to a portion of a loom side 11. I have also shown a warp beam 12 which may be provided with any ordinary let-off device such as the common rope friction let-off 13 indicated in Fig. 1. The loom is also provided with the usual crank-shaft 14 and hand wheel 15. The warp threads W are indicated as extending forward from the warp beam 12 to the harnesses, not shown.

My improved recording device comprises a drum 20, preferably formed of aluminum or other very light material to reduce inertia, secured to a hub 21 which is loosely rotatable on a supporting shaft 22. The shaft 22 is mounted in bearings 23 and 24 on a base 25, which in turn is supported on the bracket 10 previously described and may be adjusted thereon transversely of the loom.

The drum 20 is provided with an annular flange 26 enclosing a recess or chamber adapted

to receive a clock spring 27. The outer end of the spring 27 is secured at 28 to the flange 26 and the inner end of the spring 27 is secured to a stud 30 in the supporting shaft 22.

A hand wheel 31 is secured to one end of the shaft 22 and constitutes means by which the shaft may be turned to wind up the spring 27. A ratchet wheel 33 is fixed to the shaft 22 and is engaged by a pawl 34 (Fig. 2) mounted on a fixed pivot stud 35 (Fig. 3) and provided with a coil spring 36 by which the pawl is caused to yieldingly engage the ratchet wheel.

With the construction described, if the drum 20 is held from rotation, the spring 27 may be wound up to any desired extent and may be held in tensioned condition by the pawl 34.

The hub 21 of the drum 20 is preferably provided with a fine pitch spiral groove or thread 38 to receive a fine wire 40, such as a piano wire. One end of the wire 40 is secured to a screw 41 in the hub 21 and the other end of the wire is wrapped one or more times around a drum portion of the warp beam 12 and is secured to a block 42 (Fig. 1), which is clamped to the rim of the beam 12.

The spring 27 acts in such a direction as to tension the wire 40 and to rotate the drum 20 in unison with the movements of the beam 12. The ratio of diameters of the beam 12, the hub 21 and the drum 20 are such, however, that the movement of the periphery of the drum 20 is several times enlarged over the movement of the beam 12.

It will be noted that the spring 27 holds the wire 40 under continual tension and that consequently there is no substantial back-lash or lost motion between the movements of the beam 12 and the drum 20.

A roll of tape 50 of paper or other suitable material is mounted on a stud 51 (Fig. 2) in the side of a support 53, which in turn is mounted on the base 25. The tape 50 is provided with perforations 52 along its opposite edges, which perforations register with studs or projections 54 on the outer surface of the drum 20.

A spring 55 is clamped to the base 25 below the drum 20 and one end 56 of the spring extends rearward to engage the roll of tape 50 and act as a brake thereon. The other end 57 is curved upward to engage the face of the drum 20 and act as a stripper to separate the tape 50 therefrom after it has passed the recording instrument, to be described.

A pressure plate 58 is mounted at the outer

end of a spring plate 59 secured to a frame member 60 which is mounted at the top of the support 53. The pressure plate 58 holds the tape 50 firmly and smoothly in contact with the drum 20 at the recording point. The plate 58 is provided with slots 61 for the studs 54 and also with an opening 62 for the recording instrument.

This recording instrument may comprise a pen 70 clamped in an arm 71, which arm is pivoted 10 at 72 to an arm portion 73 which in turn is pivoted to the frame member 60 by a stud 74.

The arm 71 and arm portion 73 are provided with upwardly extending lugs 75 having pockets 15 on their adjacent faces to receive a spring 76 by which the arm 71 is forced downward against a cross bar 80 (Fig. 4). The cross bar 80 is mounted on pivot studs 82 and is of non-circular 20 cross section.

The bar 80 is also provided with a handle 83 25 by which it may be moved upon its pivots. When the handle 83 is raised, the bar 80 is turned to lift the pen 70 away from the tape 50 so that no record is made. When the bar 83 is turned to the position shown in Figs. 2 and 4, the bar 25 80 is lowered so that the pen 70 can engage the tape and make a record.

The arm 71 is normally pushed to one side by a spring 90 (Fig. 4) until it engages an adjustable stop screw 91. When in this position, 30 the arm 71 preferably rests on a raised portion 92 of the cross bar 80, in which position the pen 70 is out of contact with the tape 50.

A wire or cord 93 is connected at one end to a stud 94 on the arm 71 and the other end of 35 the connection 93 is secured to a stud 95 eccentrically mounted near the axis of the hand wheel 15. The intermediate portion of the connection 93 passes around suitable guiding members 96.

Each revolution of the crank-shaft 14 causes 40 the stud 95 to pull the wire or connection 93 and jerk the pen 70 sidewise. Preferably slack is provided in the connection 93 so that this jerk or pull occurs abruptly at one point in the rotation of the crank-shaft. Such a pull or jerk 45 causes the pen 70 to make a mark transversely of the tape 50 and these marks are made at equally timed intervals with respect to the operation of the loom in accordance with the rate of rotation of the crank-shaft 14.

50 At the same time, the longitudinal movement of the tape 50 corresponds to the movements of the warp beam 12, so that a record is produced showing the advance of the warp for each equally timed transverse movement of the pen 70. 55 The regularity or irregularity of the spaces between these transverse marks on the record indicates the regularity or lack of regularity in the amount of warp let-off for each pick of the loom.

60 In many looms there is a very substantial swinging of the warp beam back and forth in addition to the actual let-off movement and frequently the swinging movement is of substantially greater extent than the let-off movement. This would result in dragging the pen back and forth along a longitudinal line on the paper if it were not for the raised or cam portion 92 on the cross bar 80, which raises the pen from the paper when it is against the stop 65 91 and lowers the pen only during its transverse movement. Otherwise it is found that the continued swinging movement of the drum by the warp beam may cause the pen to perforate the paper and thus injure the record.

70 75 From the above description of my improved

recording device, it will be seen that the instrument will make a continuous record of the operation of the warp beam and let-off for any desired length of time, limited only by the capacity of the hub 21 to wind up the wire 40 as it is delivered from the flange on the beam 12.

While I have described my recording device as particularly adapted to indicate the let-off movements of a loom, the device is of more general application and may be used to record 10 data as to many other loom operations or for that matter the operations of other machines.

Having thus described my invention and the advantages thereof, I do not wish to be limited to the details herein disclosed, otherwise than as set forth in the claims, but what I claim is:

1. In a device for recording movement of a machine part and comprising a pivotally mounted drum with a record strip thereon and a marking member engaging said record strip on said drum, in combination a spring to move said drum and strip in one direction, and a retarding connection between said drum and said machine part restraining spring-actuated movement of 20 said drum.

2. The combination in a recording device as set forth in claim 1, in which the retarding connection is a fine flexible member and in which the drum has an axially extended hub on which 30 said flexible member may be wound.

3. The combination in a recording device as set forth in claim 1, in which the retarding connection is a fine flexible member and in which the drum has an axially extended hub on which 35 said flexible member may be wound, said hub having a fine pitch spiral groove to receive said flexible member.

4. In a device for recording movement of a machine part and comprising a pivotally mounted drum with a record strip thereon and a marking member engaging said record strip on said drum, in combination a spring to move said drum and strip in one direction, and a retarding connection between said drum and said machine part restraining spring-actuated movement of 40 said drum, the movement of said drum being thereby associated with the movement of the machine part, and said connection being effective to cause the movement of the drum 45 to be substantially magnified over the movement of the machine part.

5. In a device for recording movement of a machine part, in combination, a record sheet, means to move said sheet in one direction in predetermined and definite relation to the movement of said machine part and under the control thereof, whereby a given movement of 55 said record sheet corresponds to a definite associated movement of said machine part, a marking member, means to give said marking member intermittent movements in a direction transverse to said first movement but in the plane of said sheet, and means to lift said marking member from the record sheet as it approaches its 60 position of rest at one end of its transverse movement and to maintain said member in raised position between marking movements.

6. In a device for recording movement of a machine part, in combination, a record sheet, means to move said sheet in one direction in predetermined and definite relation to the movement of said machine part and under the control thereof, whereby a given movement of 65 said record sheet corresponds to a definite associated 70 movement of said machine part.

movement of said machine part, a marking member, means to give said marking member intermittent marking and return movements in a direction transverse to said first movement but in the plane of said sheet and in predetermined timed relation, and automatic means to

maintain said marking member out of contact with said record sheet during return movement of said member, whereby wear of the marking member and record sheet is greatly reduced.

OSCAR V. PAYNE.
